UNITED STATES PATENT OFFICE.

HENRY H. LAMPERT, OF CHICAGO, ILLINOIS.

BAR SUPPORT.

Application filed February 2, 1927. Serial No. 165,371.

The main objects of this invention are to provide improved means for supporting reinforcing bars used in concrete construction work; to provide a bar support and spacer particularly adapted for use in road construction for supporting the bar above the ground and for spacing it from the side molds; to provide improved means for locking the bar to the support; and to provide a bar support of this kind having improved means for retaining it in an upright position on the ground and for insuring the proper level for the bar by securing the support against being driven into the ground beyond a certain depth.

Illustrative embodiments of this invention are shown in the accompanying drawings, wherein:

Fig. 1 is a perspective, showing one form 20 of bar support and spacer in its elevated position prior to driving the pin into the ground, a reinforcing bar being shown in dotted outline, and part of a side mold being also shown.

Fig. 2 is a similar view, but showing the pin embedded in the ground.

Fig. 3 is an enlarged fragmentary top plan of the device shown in Figs. 1 and 2.

Fig. 4 is an enlarged fragmentary elevation of the same, the bar being shown in section.

Fig. 5 is a transverse section taken on the line 5—5 of Fig. 2.

Fig. 6 is a detail in elevation, showing the bearing plate.

Figs. 7 and 8 are perspectives showing other forms of bar supports and spacers.

Figs. 9 and 10 are sections taken on the lines 9—9 and 10—10 of Figs. 7 and 8 respectively.

In the form shown, the improved bar supports are used for supporting reinforcing bars 1 disposed horizontally and embedded in the concrete a uniform distance above the ground 2. Certain of the bar supports, which support the outer rows of bars, are provided also with means for spacing the outer rows a uniform distance from the vertical side walls 3 which form the molds 50 for the sides of the road.

In the constructions shown, the improved

support comprises a rod or pin having a pointed portion adapted to be driven into the ground or other supporting surface and another portion have a crook forming a seat 55 for supporting the reinforcing bar. A latch is provided for securing the bar to the seat. To insure accuracy in the placing of the reinforcing bars, means is provided also for retaining the support in an upright position 60 on the ground and for securing it against being driven beyond a certain depth. The supporting pins are preferably made of wire which possesses the essential rigidity and which may be bent readily to the desired form.

In the construction shown in Figs. 1 to 6 inclusive the support comprises a rod 4 having a pin portion 5 at one end thereof. The medial portion of the rod is bent at substantially right angles to the pin 5 to provide a head 6 adapted to receive the blows of a tool used for driving the pin in the event that the ground is not sufficiently soft to permit the pin to be driven without a tool.

Adjacent the head 6, the upper portion of the rod 5 has a crook forming a substantially U-shaped seat 7 which is slightly greater in depth than the reinforcing bar which it is adapted to support. The upper portion of the rod projects laterally beyond the crook 7 to form an arm 8 adapted to space the reinforcing bar from the mold. The reinforcing bar is secured to the seat 7 by a movable latch 9, which is adapted to span the upper part of the crook.

In the form shown, the latch 9 comprises a flat piece of metal having an aperture 10, through which one leg of the seat 7 extends 90 to provide the hinge. Formed on the other end of the latch 9, is a catch 11 adapted for interlocking engagement with the other leg of the seat. The distance between the catch 11 and the hinge of the latch is preferably 95 slightly less than the width of the seat 7 so as to necessitate springing the leg portions of the seat in opening and closing the latch. The latch is thereby held in its closed position by the resilience of the seat portion. Axial shifting of the latch relative to the upper portion of the rod is limited by shoul-

ders 12 struck out from the arm 8 and the adjacent leg of the seat 7.

Embracing the pin portion 5 of the rod, is a flat bearing plate 13 having an aperture 14 through which the rod extends. Struck out from the pin 5 on opposite sides of the plate 13, are shoulders 15 for securing the plate against axial shifting. The bearing plate 13 is spaced from the seat 7 the distance which it is desired to space the reinforcing bars above the ground or other supporting surface.

In the form shown in Figs. 7 to 9 inclusive the bar support comprises a rod 4.1 bent at 15 its medial part to form a crook 7.1 which separates a pin portion 5.1 from a spacing arm 8.1. In this form, the arm 8.1, crook 7.1 and pin 5.1 are located in the same plane, and in the forms shown in Figs. 1 to 6 inclusive, the pin 5 is offset from the plane of the crook 7 and arm 8. The throat of the crook 7.1 is restricted so as to provide a shoulder 16 which secures the reinforcing bar against accidental displacement.

25 Mounted on the crook 7.1, is a latch 9.1 which is similar to construction and operation to the latch 9 shown in Figs. 1 to 4 inclusive. In the form shown in Figs. 8 and 10, the latch is hinged to the top leg portion 30 of the crook 7.1 and in the device shown in Figs. 7 and 9, it is reversed. Axial movement of the latch 9.1 is limited by shoulders 12.1 struck out from the rod.

A bearing plate 13.1 having an aperture 25 14.1 embraces the pin 5.1 and is secured against axial shifting by shoulders 15.1 struck out from the pin.

In operation, before the supports are driven into the ground, one of the supports 40 may be used as a marker or gage for marking a line in substantially parallel spaced relation to each of the side molds 3, along which the outer rows of supports are to be driven. In using a support as a gage, it is held in 45 one hand in a plane substantially perpendicular to the mold, with the arm 8 disposed horizontally in sliding engagement with the mold and the pin 5 in engagement with the surface which it is desired to mark. The device is then moved along the mold to mark 50 the line.

The supports are then set up in spaced relation along the line, with the arms 8 engaging the mold. After the reinforcing bars 55 1 have been layed on the seats 7, the latches 9 are swung to their closed positions.

Although but certain specific embodiments of this invention have been herein shown and described, it will be understood that numerous details of the constructions shown may 60 be altered or omitted without departing from the spirit of this invention as defined by the following claims:

I claim:

65 1. A device of the class described comprising

ing a rod having a portion adapted to be driven into a supporting surface and another portion having a crook forming a seat for supporting a bar, and a latch movably mounted on said rod and adapted to span 70 said seat for securing a bar thereto.

2. A device of the class described comprising a rod having a portion adapted to be driven into a supporting surface and another portion having a crook forming a seat 75 for supporting a bar, and a latch hinged to said rod and adapted to span said seat for securing a bar thereto.

3. A device of the class described comprising a rod having a portion adapted to be 80 driven into a supporting surface and another portion having a crook forming a seat for supporting a bar, and a latch hinged to one side of said seat and adapted for interlocking engagement with the other side thereof 85 for securing a bar thereto.

4. A device of the class described comprising a rod having a portion adapted to be driven into a supporting surface and another portion having a crook forming a seat 90 for supporting a bar, and a latch hinged to said rod and adapted to span said seat for securing a bar thereto, the sides of said seat being resilient and adapted to be sprung to permit the opening and closing of said latch. 95

5. A device of the class described comprising a rod having a portion adapted to be driven into a supporting surface and another portion having a crook forming a seat for supporting a bar, a hinged latch adapted to 100 span said seat for securing a bar thereto, said latch having an opening at one end thereof through which said rod extends to form a hinge at one side of said seat, and a catch formed on the other end of said latch for 105 interlocking engagement with the other side of said seat.

6. A device of the class described comprising a rod having a portion adapted to be driven into a supporting surface and another 110 portion having a crook forming a seat for supporting a bar, and a latch hinged to said rod and adapted to span said seat for securing a bar thereto, said rod projecting laterally beyond said seat to provide a spacer 115 adapted to space the bar from a mold.

7. A device of the class described comprising a rod having a portion adapted to be driven into a supporting surface and another portion having a crook forming a seat for 120 supporting a bar, means for securing the bar to said seat, a bearing plate having an opening through which said first mentioned portion projects, and shoulders on said rod arranged to secure said bearing plate against 125 axial shifting relative to said rod, said plate being adapted to engage the top of a supporting surface.

8. A device of the class described comprising a rod adapted to be placed upright on a 130

supporting member, said rod having a crook forming a seat for supporting a bar, and a latch hinged on said rod and adapted to span said seat for securing a bar thereto.

5 9. A device of the class described comprising a rod adapted to be placed upright on a supporting member, said rod having a crook

forming a seat for supporting a bar, and a latch movably mounted on said rod and adapted to span said seat for securing a bar ¹⁰ thereto.

Signed at Chicago this 31st day of January, 1927.

HENRY H. LAMPERT.
